UNITED STATES PATENT OFFICE.

SAMUEL PRESCOTT BUSH AND JACOB CHRISTIAN LARSEN, OF COLUMBUS, OHIO, AS-
SIGNORS TO THE BUCKEYE STEEL CASTINGS COMPANY, OF COLUMBUS, OHIO.

CAR TRUCK.

Application filed September 3, 1925. Serial No. 54,299.

This invention relates to car trucks and has special reference to the spring support and the connection of the bolster with the side frame. The principal object of the invention is to provide novel means for effectually interlocking the bolster and the side frame, and to equalize the stresses on the ends of the group of springs. Other objects of the invention will appear incidental-
ly in the course of the following description, and the invention resides in certain novel features which will be particularly pointed out in the appended claims.

In the accompanying drawings, which illustrate one embodiment of the invention, Figure 1 is a side elevation of a portion of a truck having the improved construction; Figure 2 is a plan view of the same;

Figure 3 is a transverse section with parts in elevation and parts broken away.

The truck consists essentially of a side frame 1, a bolster 2, and springs 3 carried by the side frame and supporting the end of the bolster. The side frame, of course, is carried by the axles of the car wheels and it is preferably of that type in which the journal boxes 4 are integral with the frame. The side frame is formed centrally with an opening 5 to admit the end of the bolster and the bottom or floor of this opening is expanded transversely to form a spring seat 6 upon which rests an end of a spring plank 7 which extends between the two side frames of the truck. The plank 7 is of the usual channel formation with vertical side flanges 8 but the flanges terminate at and abut the inner side of the side frame, this construction aiding in keeping the side frames in parallelism. When rounding a curve, there is a concentration of stress in a plane passing across the ends of the flanges, and to overcome this strain lugs 9 are provided on the side frame so located as to snugly bear against the flanges 8, the plank being held down on the spring seat by the load transmitted through the bolster and the springs.

It is now general practice to arrange the springs in rectangular relation which arrangement requires a rather wide and weak spring seat and a corresponding width is necessary in the bolster and the opening through the side frame. In the present truck, as indicated in Figure 2, the springs are arranged in staggered relation so that

a spring in one row or line of springs will partly enter the space between two springs in an adjacent row. This arrangement reduces the width of the spring group and adjacent cooperating parts, the spread of the wheel base being reduced by the same amount that the width of the opening in the frame is decreased. It, therefore, attains strength in the truck but, to maintain the same or greater spring capacity, the length of the spring seat is relatively increased so that if the bolster should rock because of unequal loading of the car or lateral swaying of the car there is unequal strain on the ends of the spring group. The invention includes means for equalizing this strain.

The end of the bolster is formed into a nose 10 which projects into the upper end portion of the opening 5 in the side frame, and on the sides of the bolster are lugs or projections 11 which abut the inner side of the side frame and limit the extent to which the frame may be inserted over the bolster. The nose 10 is of less width than the body of the bolster and the lugs 11 terminate short of the bottom of the body, inwardly extending recesses 12 being thereby produced on the sides of the bolster, as shown in Figure 3. In the underside of the nose, near the end thereof, is a concave seat or shallow groove 13 which is adapted to rest upon a convex saddle 14 formed on the bolster spring seat 15 which forms the floor of a hood or box-like equalizer 16. This box-like equalizer or hood is closed at its outer end and has an open rear top portion, shown at 17, to accommodate the upper portion of the nose, while its sides are so shaped as to abut the projections 11 on the bolster and present tongues 18 to fit within the recesses 12 in the bolster. Near the outer closed end of the hood, lugs or projections 19 are formed on the sides thereof to abut the outer side frame. After the side frame has been fitted over the end of the bolster and the springs placed in position, the hood or equalizer is inserted to engage around the bolster end and bring the saddle directly under the seat 13. The load on the bolster and the springs will hold the saddle and the bolster together while the lugs 11 and 19 engaging the side frame will interlock the bolster therewith. Obviously, the hood or equalizer will retain its horizontal position notwithstanding rock-

ing of the bolster and the strain upon the opposite ends of the group of springs will be kept approximately even at all times.

With this construction, the side frame 5 may be easily removed from the truck if such work should be necessary. The bolster is first lifted from the springs to permit the hood 16 to be disengaged from the bolster and withdrawn. The bolster is then lowered to again rest on the springs, whereupon, 10 if the spring plank 7 with the superimposed springs and bolster be raised, the entire side frame will be free to be moved sidewise clear of the rest of the truck.

13 Having fully described our invention what we claim as new and desire to secure by Letters-Patent, is:—

1. In a car truck, the combination of a side frame having an opening therethrough, 20 the floor of the opening being laterally expanded and constituting a spring seat, a spring plank having its end resting on the spring seat, side flanges on the spring plank terminating at and abutting the side frame, 25 springs resting on the spring plank, projections on the side frame bearing against the flanges on the spring plank, a bolster having its end extending into the side frame over the springs, and an equalizer between the 30 bolster and the springs.

2. In a car truck, the combination of a side frame having an opening therethrough, a group of springs carried by the side frame, 35 a bolster projecting into the opening in the side frame over the springs, a hood housing the end of the bolster and resting on the springs, projections on the sides of the bolster abutting the inner side of the side frame, and projections on the hood abutting 40 the outer side of the side frame, the sides of the hood at the inner end thereof abutting the projections on the bolster and having tongues extending below and beyond said projections in engagement with the bolster.

3. In a car truck, the combination of a 45 side frame, a group of springs carried by the side frame, a hood resting on the springs and having tongues extending from the inner ends of its side walls, a saddle on the floor of the hood, projections on the sides of 50 the hood abutting the outer side of the side frame, and a bolster having a reduced end forming a nose to engage within the hood and having a seat in its under side resting on the saddle, the bolster having projections on 55 its sides abutting the inner side of the side frame and the end of the hood and having recesses below said projections to receive the tongues on the hood.

4. In a car truck the combination of cast 60 integral side frames comprising upper and lower members, columns connecting the two, a bolster opening, a bolster in the opening, means between the bolster and the springs 65 interlocking with the bolster for equalizing the strains on the ends of the group of springs, stops acting against the outer sides of the columns cast integral with said equalizing means and stops cast integral with the bolster and acting against the inner sides of the columns, whereby under 70 normal conditions the frames are prevented from displacement with respect to each other, but may be withdrawn without requiring material disturbance of the springs. 75

5. As a new article of manufacture, a truck bolster having integral inside bolster stops and separate outside bolster stops adapted to interlock with the bolster, said 80 separate stops providing means above the springs for equalizing the compression of individual springs in each group of springs at opposite ends of the bolster.

In testimony whereof, we have signed this specification.

SAMUEL PRESCOTT BUSH.
JACOB CHRISTIAN LARSEN.
